(57) **CLAIM**

The ornamental design for a sampling device, as shown and described.

DESCRIPTION

FIG. 1 is a front perspective view of a sampling device according a first embodiment, with one analyte pathway and position aid markings.

FIG. 2 is a back perspective view thereof.

FIG. 3 is a front elevational view thereof.

FIG. 4 is a back elevational view thereof.

FIG. 5 is a top elevational view thereof.

FIG. 6 is a bottom elevational view thereof.

FIG. 7 is a left side elevational view thereof.

FIG. 8 is a front perspective view of a sampling device according a second embodiment, with one analyte pathway, two blind analyte pathways, and position aid markings.

FIG. 9 is a back perspective view thereof.

FIG. 10 is a front elevational view thereof.

FIG. 11 is a back elevational view thereof.

FIG. 12 is a top elevational view thereof.

FIG. 13 is a bottom elevational view thereof.

FIG. 14 is a left side elevational view thereof.

FIG. 15 is a front perspective view of a sampling device according a third embodiment, with two analyte pathways and position aid markings.

FIG. 16 is a back perspective view thereof.

FIG. 17 is a front elevational view thereof.

FIG. 18 is a back elevational view thereof.

FIG. 19 is a top elevational view thereof.

FIG. 20 is a bottom elevational view thereof.

FIG. 21 is a left side elevational view thereof.

FIG. 22 is a front perspective view of a sampling device according a fourth embodiment, with three analyte pathways and position aid markings.

FIG. 23 is a back perspective view thereof.

FIG. 24 is a front elevational view thereof.

FIG. 25 is a back elevational view thereof.

FIG. 26 is a top elevational view thereof.

FIG. 27 is a bottom elevational view thereof.

FIG. 28 is a left side elevational view thereof.

FIG. 29 is a front perspective view of a sampling device according a fifth embodiment, with four analyte pathways and position aid markings.

FIG. 30 is a back perspective view thereof.

FIG. 31 is a front elevational view thereof.

FIG. 32 is a back elevational view thereof.

FIG. 33 is a top elevational view thereof.

FIG. 34 is a bottom elevational view thereof; and,

FIG. 35 is a left side elevational view thereof.
